PHOTOELECTRIC TUBE

Fritz Schröter, Berlin, Germany, assignor to
 Telefunken Gesellschaft für Drahtlose Tele-
 graphie m. b. H., Berlin, Germany, a corpora-
 tion of Germany

Application May 31, 1930, Serial No. 458,059
 In Germany June 6, 1929

2 Claims. (Cl. 250—27.5)

In all technical uses of photoelectric tube actions it is desirable that the electric current of the photoelectric tube which is caused to flow by the action of incident or diffusely reflected light should be as large as possible. In the case of vacuum tubes, the said current is a pure electronic current. The incident light causes the issuance of electrons from the surface layer or a layer adjacent to the surface of the photoelectrically active material while incidentally overcoming a certain resistance known as the "escape work" or "work function", of which terms the former will be used throughout this description. The number or volume of said electrons emitted is proportional to the intensity of the light, while their maximum speed is a function of the wave-length of the light. The energy supplied to the electrons from the light and therefore their initial velocity grows with increasing frequency of the light. However, inasmuch as each electron must first be furnished with a certain minimum amount of energy in order that it may be enabled to escape from the surface layer of the photoelectrically active material, there exists what is known as the "limital wavelength" of the light peculiar to the material so that beyond this critical value, in the direction of greater wave-lengths, no more photoelectric effect may arise. By the use of the term "limital wavelength" applicant is intending to designate the wave-length of that light whose energy is equivalent to the escape work or work function hereinabove mentioned and, therefore, refers to the limiting light values for producing the effects desired.

In the case of gaseous tubes, in the presence of a sufficiently high supplementary potential, the said primary electron current, in addition, will cause the flow of a far heavier secondary ionic current whereby the effectiveness of the photoelectric tube is greatly enhanced.

Now, the purpose of the present invention is, by the adoption of ways and means to be described in more detail further below, for example, to improve or increase from photoelectric tubes the yield of current by raising the primary electron current, and, in the case of gaseous tubes, also the aggregate current consisting of the electron and the ion currents by reason of a diminishing of the so-called "escape work". Simultaneously therewith, a shift in the limital wave-length towards greater wave-lengths may also be obtained. From this shift, among the advantages which may be obtained are, for example, the following:—

(1) A great number of substances whose limital wave-length falls well inside the short-wave range become thus photoelectrically useful in practice;

(2) Other substances which, to be sure, exhibit a photoelectric effect in the white range, result in an increased yield of current seeing that the portion of the white light possessing greater wave-length is also rendered active; and,

(3) By rendering the photoelectric material more sensitive or responsive in the direction of the longer waves, a responsiveness heretofore unknown is insured for certain spectral ranges and purposes such as are required for the picture-telegraphic transmission of multi-color copies.

The invention as herein set forth has been schematically illustrated by the accompanying drawing, of which Fig. 1 represents a preferred form and discloses a means by which a photoelectric cathode may be heated; and,

Fig. 2 discloses a modification of the invention wherein the photoelectric material is arranged in a predetermined manner as a support surface.

Among the measures and means that may be mentioned to insure a decrease in the "escape work" of the electrons as they issue from the photoelectric material, as will become apparent from reference to the drawing, the following may be considered useful according to this invention:—

1. Changes in the surface film of the photoelectrically active material by chemical actions or by the physical or mechanical addition of surface layers of an extraneous substance, it having to be noted that the latter need not necessarily be photoelectrically active. It is known in the prior art, and, in fact, it has been customary with potassium tubes to "hydride" the potassium cathode superficially, or, in other words, to cover it with a layer of potassium hydride. While this process merely serves the purpose of insuring a more perfect energy absorption of the light, according to this invention a layer of a substance is to be applied which, as is usually done, for instance, with the filaments of thermionic tubes, tends to diminish the "escape work" to be overcome by the electrons as they escape therefrom. The substances which may be considered for this purpose are, e. g., the oxides of alkali-earth metals or else a thin barium or thorium film. The thickness of the film need to be only a few atoms diameter so that the film itself will still be sufficiently permeable for the light;

2. Heating of the photoelectrically active material to a constant though sufficiently high temperature. By heating such a pure or a thoriated conductor, or a conductor coated as mentioned above in 1, with a layer of baryta, etc., an active thermal movement of the negative electricity carriers is occasioned; and if the temperature is adequately high, this results in "voluntary" or spontaneous escape or evaporation of the electrons from the material, as by the Richardson effect. If the cathode is illuminated or irradiated at the same time, this results in a further growth in electron emission inasmuch as such additional energy supply enables a still greater number of such electrons to escape as previously or priorly possessed only velocity which was inadequate to cause them to leave the surface layer of the cathode. The purely thermo-electric current also flowing in the dark state of the photoelectric tube, since it is constant, can, if desired, by suitable circuit means be separated from the component or part due to the illumination only. The heating of the photoelectric cathode is effected most suitably by electrical means, although this is not essential. The cathode itself may be traversed by the heating current, or else the heater body may be separately disposed, heat being thus supplied therefrom to the photoelectric layer by virtue of conduction or radiation. It is an embodiment of this kind which has been shown by Fig. 1, wherein the photoelectrically active cathode (1) is applied upon a hollow body (2) which is entirely or partly closed and consists of electrically insulating material. The body (2) is then internally heated by means of a heater wire (3) connected with an external source of current (not shown).

The third consideration may be that of influencing the surface of the photoelectrically active material by an electric field. The issuance of photoelectric electrons from the surface of the conductor can be facilitated by causing a suitably acting electric field to affect the lattice of atoms of the photoelectrically active material in the surface so that it tends, as it were, to pull out the electrons therefrom. It is advantageous for this purpose to bring as high a field density as possible to act upon the surface layer. Such a special increase of the relatively low field density due to the potential applied thereto normally in the operation of a photoelectric tube, according to this invention, can be effected by providing the surface of the cathode 1 with peaks, points or edges of small radius of curvature as illustrated

in Fig. 2. Instead of marked points or edges shown by Fig. 2, recourse could also be had to a more or less regular roughening of the cathode surface.

Another chance of causing a high field density (intensity) to act upon the photoelectrically active material would consist in applying upon the said surface a thin coat of an electric semiconductor or poor conductor. In such a layer even a relatively feeble current will cause a high fall of potential, or, in other words, a high field intensity. What has further a favorable influence upon the electron yield in connection with such an arrangement is the circumstance that an outside electric field will penetrate more deeply into such a poor conductor than into a nearly perfect conductor, and also that electron layers located at great depths are thus made accessible to the influence. It may be of advantage also to use an alternating current of low or of higher frequency to act as the anode potential in the operation of such a photoelectric tube. The capacity or wattless current flowing through such a tube which inside the layer of the poor conductor may partly continue as a conduction current will cause therein the permanent maintenance of the requisite fall of potential.

From the above description it is apparent that many modifications of the method and means herein disclosed may be made, and I, therefore, believe myself to be entitled to make and use any and all of such modifications as fairly fall within the spirit and scope of the hereinafter appended claims.

Having now described my invention, what I claim and desire to secure by Letters Patent is the following:

1. A photoelectric device comprising a hollow insulating support member, a coating of light sensitive electron emitting material supported on one outer surface of the hollow insulating support member, and a filamentary heating unit contained within the hollow insulating support member and covering an area substantially co-extensive with the light sensitive material.

2. A photoelectric device comprising an insulating member, a photoelectric coating positioned upon one surface of the insulating member, and a filamentary heating unit supported by the insulating member and covering an area substantially co-extensive with the light sensitive material and separated thereby from the electron emitting coating.

FRITZ SCHRÖTER.
